W. D. LOUGH

ADJUSTABLE WELL CASING AND SAND SCREEN

Filed May 21, 1923

UNITED STATES PATENT OFFICE.

WILLIAM DAVID LOUGH, OF SCOTT CITY, KANSAS.

ADJUSTABLE WELL CASING AND SAND SCREEN.

Application filed May 21, 1923. Serial No. 640,543.

To all whom it may concern:

Be it known that I, WILLIAM DAVID LOUGH, a citizen of the United States, and a resident of Scott City, in the county of

5 Scott and State of Kansas, have invented a new and useful Improvement in Adjustable Well Casings and Sand Screens, of which the following is a full, clear, and exact description.

10 My invention relates to improvements in adjustable well casings and sand screens, and it consists in the combinations, constructions, and arrangements herein described and claimed.

15 An object of my invention is to provide a device of the character described for the purpose of developing wells for large capacities of water production by providing a larger seepage area for letting water into 20 the well, such devices being especially suitable for municipal water supplies and irrigation systems.

A further object of my invention is to provide a device of the character described 25 that will function particularly well in sand and gravel strata.

A further object of my invention is to provide a device of the character described that is constructed entirely of non-corrodible materials and which therefore precludes 30 the accumulation of metal salts which might have an ill-effect upon the water.

A further object of my invention is to provide a device of the character described 35 that may be quickly and easily sunk in a position for use.

A further object of my invention is to provide a device of the character described 40 in which the superimposed segments may be spaced at a predetermined distance from one another to most readily adapt the device to the particular characteristics of the soil or strata in which it is used.

45 Other objects and advantages will appear in the following specification, and the novel features of the invention will be particularly pointed out in the appended claim.

50 My invention is illustrated in the accompanying drawings, forming part of this application, in which—

Figure 1 is a partial sectional view of an embodiment of my invention, and

55 Figure 2 is an enlarged fragmentary view of the mechanism illustrated in Figure 1, partly in section.

In carrying out my invention, I make

use of four metal rods 1. A circular steel cutting shoe 2 is provided with openings 3 therethrough, through which the rods 1 are projected and held against upward 60 movement by integral head portions 4. The lower circular edge 5 of the steel cutting shoe is relatively sharp, as indicated in Figure 1, so that the shoe may be easily forced into the water bearing strata in the well 65 bore 6.

A plurality of convex concave vitrified clay annular sections 7 are each provided with openings 8 therethrough in registration with the openings 3 of the steel cutting shoe 2, and are arranged to be threaded upon the bolts 1 in the manner shown in Figure 1. Non-corrosive spacing washers 9 are disposed concentric to the bolts 1, one between each of the vitrified tile sections 7. 70 These washers are preferably constructed of bronze, but may be of copper, babbitt, or any other non-corroding material.

The concave side of the sections 7 has its side walls 10 at a greater pitch from the 80 horizontal plane than its side walls 11 of the convex side, and therefore the distance between the sections 7 from the peripheral edges thereof toward the bolts 1 at the base of the convex and concave side walls, widens 85 gradually, so that particles of sand or gravel in the well bore may not clog the spaces between the sections. Obviously, if it is desired to space the sections 7 at a greater distance apart from that shown in Figure 90 1, or closer together, it is merely necessary to vary the thickness of the spacing washers 9. Therefore the device may be adapted to coarse strata or a gravel and sand strata.

The portion of the device intended to 95 convey water to the pump mechanism is constructed precisely the same as the sand screen section, but the washers 9 are not placed between the sections. The sections so placed are indicated at 12 in Figure 1. 100 The uppermost of the sections forming the casing through which water is conducted to the surface is flat, as shown at 13, so that a suitable pipe may be attached by means of the bolts 1 to the uppermost section. It 105 will be noted that the only difference between the assembly of the device or that portion which is indicated to permit the seepage of water therethrough and that portion which is indicated to merely convey the 110 water, is that the washers 9 are omitted in one and are not omitted in the other.

2

From the foregoing description of the various parts of the device, the operation thereof may be readily understood. In sinking my improved well casing and sand screen, the work is greatly facilitated due to the fact that the entire screen and well casing is constructed of annular sections which are virtually threaded upon vertical bolts 1 projected through the steel cutting shoe at the lower end of the bolts. By use of this simple structure, the sections may be applied one at a time, or if conditions permit, a plurality of sections may be assembled and the unit sunk into the well bore. 5

15 If it is found that the water bearing strata is a relatively fine sand, it would be necessary to surround the sand screen with coarse gravel and the spaces between the sections should be relatively narrow. The sand and 20 the gravel will not enter the casing, however, since the space between the sections permit its entrance. It will therefore be apparent that in my present invention I have provided a sand screen that may be adjusted at 25 will to completely adapt the screen to the water bearing strata in a manner to permit the maximum amount of seepage without danger of the entrance of the sand or gravel to the casing. 30 It will also be apparent that the space between the sections will not become clogged

by exceedingly fine portions of the gravel which may seek their way between the sections, since the space between the sections widens toward the interior of the sand screen, a fact which would compel the movement of the gravel once it had passed through the adjacent outer edges of the sections to move entirely within the casing where it would fall upon the bottom of the sand screen and remain until flushed out. 35 40

While I have here described the sections 7 as annular, it should be noted that any tubular section, such as a rectangular section in place of an annular section, may be employed with equal success, a condition which of course must be determined entirely by the conditions governing the particular use of the casing. 45

50 I claim:

A device of the character described comprising a plurality of movable sections having a convex end wall and a concave end wall, the angle of inclination of the concave wall being greater than the angle of inclination of the convex wall, rods for mounting said movable sections in axial alignment with one another, and separable spacing members for spacing certain of said sections back from one another a predetermined distance, whereby water may enter said casing. 55 60

WILLIAM DAVID LOUGH.
